UNITED STATES PATENT OFFICE.

GEORGE W. SNAMAN, JR., OF ALLEGHENY, PENNSYLVANIA.

TOY.

SPECIFICATION forming part of Letters Patent No. 479,534, dated July 26, 1892.

Application filed August 8, 1891. Serial No. 402,146. (No model.)

To all whom it may concern:

Be it known that I, GEORGE W. SNAMAN, Jr., of Allegheny, in the county of Allegheny and State of Pennsylvania, have invented a new and useful Toy, of which the following is a full, clear, and exact description.

This invention relates to a novel device for the amusement and instruction of children; and it consists, essentially, of a small cabinet holding picture-slides in series which are spring-pressed upwardly, each slide being held depressed by sets of rods that extend to letters on a forward alphabet-board. When the set of rods which restrain a picture-slide are properly manipulated to spell the name of the object represented by the picture, said slide is released and upwardly projected to display the picture thereon.

My invention further consists in the construction and combination of parts, as is hereinafter described and claimed.

Reference is to be had to the accompanying drawings, forming a part of this specification, in which similar letters of reference indicate corresponding parts in all the figures.

Figure 1 is a front perspective view of the device. Fig. 2 is a plan view in section on the line 2 2 in Fig. 1. Fig. 3 is an interior view, broken, showing parts of the contained mechanism. Fig. 4 is a plan view of a modification. Fig. 5 is a cross-section taken on the line 5 5 in Fig. 4; and Fig. 6 is a broken longitudinal section of parts shown in Fig. 4, taken on the line 6 6 in Figs. 4 and 5.

The most simple form for constructing the device is shown in Figs. 1, 2, and 3, and consists of working parts contained in a small casing or cabinet A.

The cabinet may be given different forms, but preferably is made rectangular, laterally considered, and at a proper distance from the front edge has a box-like formation B projected above the part C in advance of the same, which latter has a flat top surface, as shown in Fig. 1. The rear wall of the portion B is vertically channeled at intervals to adapt it to afford grooves that are preferably dovetailed on their parallel side edges, which grooves loosely retain a series of slides D, that are formed on their side edges to correspond with those of the grooves they enter and have such a proportionate length as will permit

their upper edges to align with each other and with the top of the rear wall when fully depressed. Each of the slides D has a forwardly-projecting ledge a produced on its lower edge, and from said ledges a pin or hook b is sufficiently projected on the front edge of each to engage with a spring c, which may be a gum band, as shown, or of any other suitable form and character, as preferred.

Across the inner surface of the rear wall of the cabinet A, a short distance below the top edge of the wall, a keeper-bar d is secured, which is furnished with a series of pins or hooks e, that vertically align in pairs with the hooks or pins b below them, and upon each pair of said pins one of the said springs c is placed in a slightly-stretched condition.

It will be seen from the manner of connecting the springs c with the slides D and keeper-bar d that the slides will be normally held in elevated adjustment by the tension of the springs, which will elastically yield or stretch and allow the slides to be depressed within the cabinet A when said slides are pressed upon by the operator.

The top side of the front section C on the cabinet A has several rows of spaced slots e' formed in it, which slots in number may be equal to the number of letters in the alphabet, or a less number may be provided, if preferred, all of the slots extending in parallel lines from the front toward the rear of the table or top wall of the section C. As shown in Figs. 2 and 3, there are rods g, of any proper material, extended from the slots e' rearward and are loosely secured to slide freely by staples g'. Each rod g has its front end bent upward and projected through a slot e', so as to be readily manipulated.

Letters of the alphabet are affixed in any desired order on the top face of the section C, one letter being located adjacent to each slot. Preferably they are arranged in sequence from "A" to "Z," if so many letters are needed in the formation of the device.

Upon the slides D, facing the front of the cabinet A, a pictorial representation of any familiar animal or object is painted or secured, a different picture being placed on each slide. A proper number of rods g are extended toward a slide D from the slots e' and caused to bear on the ledge projected

therefrom, the length of said rods being such that their upwardly-bent end portions will lie near to the rear terminals of the slots they are located in when their opposite ends are 5 engaged with a slide-ledge *a*.

The indicating-letters of the alphabet that are severally adjacent to the front ends of the rods *g*, grouped toward a slide *D*, should 10 spell the name of the animal or object represented on said slide, and it is essential that the ends of the rods *g* should be disposed in such order as will allow the representative letters therefor to be spelled properly as each 15 rod is withdrawn from the engaged ledge.

15 To illustrate the operation, if the picture of a cat should be affixed upon the upper slide in Fig. 2 the rods *g*, leading from the slots, will be indicated by the letters "C," "A," and "T," and preferably the rod carrying "A" is made to 20 bear on the ledge *a* at one side of the pin *b* and the rods carrying "C" and "T" on the other side of said pin. When the rods *g* are pulled in the order required to spell "Cat," the slide whereon a cat is illustrated will be released, 25 and the contraction of the spring *c* will cause it to throw the slide upward until its ledge *a* strikes against the lower edge of the keeper-bar *d*, which will limit the upward projection of the slide and fully expose the depiction of 30 a cat on its front face.

Any desired number of slides *D* may be provided, and in case the same letter of the alphabet is used to spell the names of animals or objects on different slides a supplementary 35 rod *g*² is connected with the main rod *g*, as shown in Fig. 2, where the letter "D" is found in the words "Bird" and "Dog," that are illustrated on two slides; also, the letter "O" in the names "Dog" and "Horse" is provided 40 with a main rod and a supplementary rod to apply the letter to each name on the separate slides.

In case the supplementary rods *g*² are used, it will be evident that both the main rod and 45 the supplementary rod will be moved when the main rod is actuated. This will not have any effect on the slide that is to remain concealed, as it is necessary that all of the rods on a ledge be withdrawn from it before the 50 slide will be released, and to secure efficient action the rod that represents the last letter of the name of the object on the slide should be located near the center of the ledge on said slide, so that the picture will remain concealed until all the rods on the ledge have 55 been properly drawn from the slide.

In Figs. 5 and 6 a slightly-modified form for the slide-holding device is shown, which 60 consists of a set of trigger-bolts *i* for each slide *D*, that are supported to slide toward or from the picture-holding slides, which latter are arranged in parallel series on two walls at the rear of the cabinet *A*, as shown in Fig. 4, and adapted to slide upwardly. The trigger-bolts *i* loosely engage two parallel walls *n* 65 *o* (see Fig. 5) and are arranged in sets. Each group representing the proper letters to spell

the name of the object illustrated on the slide engaged by the grouped trigger-bolts has rods *g* loosely attached to its front end, 70 which rods are pivoted forwardly to rock-arms *p*, which are loosely supported by pintle-bolts *p*' in slots formed in the top wall of the cabinet-section *C*, the arms *p* having button-heads *p*² on their upper ends, which when 75 depressed will draw the trigger-bolts and release them from engagement with the ledges *a*, whereon they rest when the slides *D* are depressed to conceal the pictures on their faces. 80

As represented in Fig. 6, the trigger-bolts *i* in each group are arranged in oblique rows in the supporting-walls *n o*, so that they will bear one at a time on a picture-slide ledge, the bolt which represents the first letter of 85 the name to be spelled being lowermost in the group and the first to be withdrawn. A spring *r* is placed on each trigger-bolt to normally project it toward the ledges *a*. Each of the trigger-bolts has its end that engages with a 90 ledge *a* sloped, as indicated in Fig. 5, and the ledge is also undercut on its forward edge, so that a draft on each trigger-bolt will allow the picture-slide to rise until it strikes the next bolt of the group, and so on until the name is 95 spelled properly, and the picture-slide is upwardly projected until its ledge strikes the cross-bar *d* or on the lower edge of the guide-wall *a'*, that is parallel with and in front of the outer rear wall of the cabinet *A*. 100

The means for restraining the slides *D* and releasing the same, just described, is best adapted for a cabinet of considerable dimensions holding a number of slides, while the plan of construction first explained is more 105 simple and cheaper to produce, both embodying the same general features of construction.

It is claimed for the toy herein shown and described that it will be of great advantage in 110 the instruction of children by exemplifying the significance of letters and their combinations to form words of one syllable and at the same time amuse the scholar, whose ingenuity is taxed to produce the necessary combinations for a release of the pictures. 115

Having thus described my invention, what I claim as new, and desire to secure by Letters Patent, is—

1. A toy comprising a cabinet, independent 120 vertically-movable picture-slides therein, a contractile spring for each slide that elevates the slide, a set of reciprocating trigger-rods for each slide, adapted to hold it depressed and release it when all the rods of a set are 125 moved, and a letter for each rod, substantially as described.

2. The combination, with a cabinet and a series of independent picture-slides vertically movable therein, of a transverse cross-bar in 130 the cabinet, a contractile spring for each slide, connecting it with the cross-bar and adapted to separately move its connected slide, a set of connectible reciprocating trigger-rods for

- each slide, which release it when all the rods for a slide are retracted, and an appropriate designating-letter for each trigger-rod, substantially as described.
- 5 3. The combination, with a cabinet, a series of independent picture-holding slides vertically and separately movable therein at one end of the cabinet, and a transverse bar in the cabinet near the slides, of a contractile 10 spring for and connecting each slide with the cross-bar and normally elevating said slide, a set of longitudinally-movable trigger-rods for each slide, together adapted to hold the slide depressed and its spring stretched until all 15 the rods of a set are retracted, and an alphabetic letter for each rod of a set that in proper order indicates the name of the pictured representation on the slide, substantially as described.
- 20 4. The combination, with a cabinet having an elevated rear section and a lower front section having series of slots in its top wall, a series of picture-holding slides vertically movable on the rear wall of the cabinet, and a 25 horizontal cross-bar in the cabinet and near the slides, of a spring for each slide, connecting it and the cross-bar, and a set of detent

trigger-rods for each slide, extended from the slots in the cabinet-wall to engage ledges on the lower end of the slides, each rod being 30 designated by a letter of the alphabet and each set of rods adapted to hold a slide depressed and its spring stretched, substantially as described.

5. The combination, with a cabinet having 35 an elevated rear section and a lower front section having a series of slots in its top wall, a series of picture-slides vertically movable on the rear wall of the cabinet, each slide provided with a forwardly-projecting transverse 40 ledge at its lower end, and a horizontal cross-bar in the cabinet, near the slides and above the ledges, of a retracting-spring connecting each slide with the cross-bar, a set of longitudinally-movable trigger-rods for each slide, 45 adapted to loosely engage its ledge, supplementary rods for some of the trigger-rods, and a designating-letter for each main trigger-rod, substantially as described.
